ATTACHABLE RIBBING FOR INNERSOLES AND INNERSOLE EQUIPPED THEREWITH

Filed Oct. 18, 1928

UNITED STATES PATENT OFFICE

PERCY W. VALENTINE, OF NATICK, MASSACHUSETTS

ATTACHABLE RIBBING FOR INNERSOLES AND INNERSOLE EQUIPPED THEREWITH

Application filed October 18, 1928. Serial No. 313,252.

This invention relates to material for attachment to innersoles to provide the rib in which the stitches of the inseam are placed for securing the upper, innersole and welt together in the manufacture of 5 welt shoes. It has long been a common practice to make innersole bodies out of leather or inferior quality, leather-board, and other materials which are either not strong enough 10 or not thick enough to permit of the stitch receiving rib being made by cutting and turning up an integral flap from the body (as in the practice in the case of innersoles made of high grade leather), and to make 15 the rib out of a separate strip of textile fabric folded lengthwise to form an upstanding part, which I will call the rib proper for the purpose of convenient definition, and outstanding flanges or flaps at the base 20 thereof through which the stitches are passed in attaching the rib to the body of the sole.

The ribs so formed are usually reinforced, either by a separate strip of material placed 25 between the folds of the fabric forming the rib proper, or by an integral part of the fabric strip folded back under one of the attaching flanges and turned up at its edge into the rib proper. Both of these modes 30 of reinforcement provide three thicknesses of material in the rib, and the second one also makes one of the attaching flanges a two-ply structure. Both require material 35 in excess of that needed to make merely the rib proper and its flanges, and also a special operation, that of placing the reinforcing strip or flap properly within the rib, and the ribbing of both these descriptions which is made as a finding for sale to shoe makers, 40 is stitched at the base of the rib proper to hold the rib in shape and the reinforcement in place.

My object is to provide a manufactured 45 textile rib or ribbing for the use above indicated, containing in its woven structure means for securing together the plies which make the sides of the rib proper, and thereby reinforcing the rib. Secondary objects resulting from the foregoing are the saving 50 in material and labor through elimination of

reinforcing material and of the operations of folding the rib and stitching its sides together; and the formation of non-raveling edges on both flanges of the rib.

The invention comprises a new ribbing 55 for the purpose specified which is woven with binder threads or yarns passing back and forth between the plies of the rib proper and having selvages at the edges of both flanges; and it further comprises a 60 complete innersole consisting of a body combined with an attached rib of the character above set forth.

In the drawings,

Fig. 1 is a plan view, and Fig. 2 a cross-section on line 2—2 of Fig. 1, of an innersole embodying the present invention;

Fig. 3 is a perspective view on an enlarged scale of a fragment of ribbing material embodying this invention;

Fig. 4 is a cross-section on line 4—4 of Fig. 3, drawn on a still larger scale illustrating the woven construction of the material;

Figs. 5 and 6 are longitudinal sections on 75 lines 5—5 and 6—6, respectively, of Fig. 4, further illustrating the construction.

The innersole comprises a body *a* and an applied strip of ribbing material having a rib proper *b* and flanges or flaps *c* and *d*, 80 which are attached to the body by sewed seams *e*, *f* and *g*. In the elements and mode of connection thus far described, the present invention does not differ from articles of the prior art. Its novelty consists in the 85 structural characteristics of the rib, and in the new combination comprised by the union of such novel rib with an innersole body which may be either new or old.

Referring now to the structural detail 90 views, Figs. 4, 5 and 6, the ribbing material is seen to be a woven fabric consisting of warp threads 1, 1, and weft or filling threads 2. The rib *b* consists of an intermediate 95 part of the fabric doubled to form two plies which lie contiguous to one another and are securely held in that relationship by binder warps 3, 3.

The binder warps are interwoven with the filling threads in the course of original 100

manufacture of the material. By a suitable arrangement of warp threads and harnesses, the shuttle thread is caused to pass between the warps of the flange *d*, for instance, and the adjacent ply of the rib proper, then reverse, to pass between the warps of the opposite ply of the rib proper and those of the flange *c*. On again reversing, with change of the sheds, the filling thread passes in the opposite order between the warps of the flange *c* and the adjacent ply of the rib proper, and then between those of the other ply and the adjacent flange *d*. During weaving, of course, the flanges *c* and *d* are parallel to one another. The binder warps are placed in a width sufficient to tie together the two plies thus woven for a width equal to the desired height of the rib proper, leaving them unconnected for the rest of their width, and therefore in a condition to be separated and spread apart at right angles to the rib proper when applied to the body of the innersole.

The weaving method above described is not my invention and is not claimed as such herein. But the application of this or any equivalent method to the production of an innersole rib, and the ribbing material having the resultant characteristics, are my invention, for which I claim adequate protection.

The article containing the characteristics above described has numerous obvious advantages, among which may be named the following:

The side plies of the rib, being tied together, not only throughout the length of the rib but also at frequent intervals from base to summit, are not only prevented from separating, but are also reinforced and stiffened, each by the other. Thus the rib requires no additional reinforcement to hold it upright when attached to the sole. The outer edges of both flanges are selvages, wherefore they will not ravel. This is a feature not possessed by ribbing made of strips cut from a sheet of cloth, for both edges of all strips so cut, except those cut from the extreme edges of the sheet, are raw edges; and even the strips cut from the edges of the sheet are raw at one edge. These useful characteristics are obtained with the utmost economy, for there is no separate reinforcing strip or cord, neither is it necessary to provide the strip with excess width in order to provide material to fold back under one of the flanges and into the rib proper; and the additional operations of placing the reinforcement and stitching the sides of the rib together are obviated. Instead only the minimum of material needed to make a rib of given height with flanges of given widths is used, and the binding together of the sides of the

rib is performed in the course of weaving the fabric.

What I claim and desire to secure by Letters Patent is:

1. An innersole comprising a body and a separate attached stitch-receiving rib formed of textile fabric, having contiguous plies forming the sides of the rib, and binder warps interwoven with filling threads of both plies. 70

2. An innersole comprising a body and a separate attached stitch-receiving rib made of textile fabric; said rib having a rib proper formed of plies of the fabric arranged side by side and flanges projecting 80 oppositely to one another from the base of such rib, and including structural strands or threads interwoven with both plies. 75

3. Fabric ribbing for innersoles comprising a woven structure having plies arranged 85 side by side to form a rib proper and structural strands woven back and forth between said plies in the rib proper. 80

4. Fabric ribbing for innersoles comprising a woven structure having plies arranged 90 side by side to form a rib proper and including binder strands woven back and forth between said plies; one of the plies being extended from the part in which said binder strands are located and from the 95 other ply, to form an attachable flange. 90

5. A rib strip for attachment to innersoles having a rib proper and separate attaching flanges at opposite sides of the base of said rib proper; said strip being composed of a woven fabric doubled longitudinally in its middle part to form plies extending side by side between the summit and the base of the rib and including structural strands interwoven with both of 100 said plies. 100

6. A rib strip for attachment to innersole bodies comprising a textile fabric having a warp and filling strands doubled lengthwise throughout a portion of the width of the 110 strip to form a rib proper, and binder strands interwoven with the crossing strands in those parts of both plies which form the sides of the rib proper. 110

7. A rib strip for attachment to innersoles, having a rib proper and attaching flanges at opposite sides of the base of the 115 rib proper; said strip being a unitary fabric composed of interwoven warp and weft strands and binder strands woven through 120 the rib proper, and formed with selvages at the outer edges of both flanges. 120

8. A textile fabric rib strip for attachment to innersoles, comprising a two-ply rib proper containing binder strands interwoven with both plies thereof, and single 125 ply flanges each being a part of one of said plies. 125

9. A fabric strip adapted to provide the stitch-receiving ribs of innersoles, comprising 130

ing textile fabric plies extending side by side and containing interwoven binder strands in a fractional part of their width, which part constitutes the rib proper, and
5 said plies being otherwise unconnected from the rib proper to their outer edges and adapted to form flanges.

10. A fabric strip adapted to provide the stitch-receiving rib of an innersole consisting of interwoven longitudinal warp and transverse weft or filling threads, the fabric so formed having selvages at both edges and being of folded formation intermediate such edges to provide two plies lying side by side from the fold; a part of the warp threads being binder warps passing back and forth between the wefts of said plies in a portion only of the width from the fold to the nearer selvage edge, forming
15 thereby a rib proper; the plies of the fabric adjacent to said selvage edges being separable from one another and providing flanges for attachment to the body of an innersole.

In testimony whereof I have affixed my
25 signature.
